UNITED STATES PATENT OFFICE

HENRY WILLIAM HAEGLER, OF GENEVA, SWITZERLAND

CARBURETOR

Application filed June 5, 1924, Serial No. 717,998, and in France July 28, 1923.

The present invention relates broadly to the art of carburetion, and more particularly to this art as adapted for use with internal combustion engines.

5 It has heretofore been proposed to provide heating means on carburetors, operable simultaneously with the operation of the choke for assisting in vaporizing the fuel during such periods as the engine fed by the carburetor is 10 cold or is being started. It is also old to provide a fuel control and electrical heating means coupled with a supplemental air valve for varying the amount of heat automatically as the supplemental air varies, but without 15 changing the ratio of carburant to air. Controls of this character are of decided advantage, whether operated manually or automatically, and it is one of the objects of the present invention to embody the advantageous 20 features thereof in a carburetor having fixed fuel feed nozzles, and operable independently of the choke. In accordance with the present invention, therefore, I provide heating means and means for controlling the effective 25 suction on the fuel nozzles operable simultaneously for giving at all times the desired proportion of carburant and air, the ratio of carburant to air, however, being progressively variable.

30 It is well recognized that if a carburetor is adjusted to give maximum power with a hot motor and normal consumption of carburant, its efficiency is but mediocre when the engine is cold. On the other hand, with a carburetor 35 adjusted for a hot motor, difficulty is frequently experienced in starting, particularly during cold weather. It is one of the purposes of the present invention to provide means for maintaining not only high efficiency 40 at all times during the operation of the engine, but to insure a carburetor by means of which starting, even in cold weather, and idling will be greatly expedited.

In the accompanying drawings there is 45 shown more or less diagrammatically, for purposes of illustration only, one embodiment of the invention, it being understood that the drawings do not define the limits of my invention, as changes in the construction and 50 operation disclosed therein may obviously be

made without departing from the spirit of the invention or scope of my broader claims.

In the drawings:

Figure 1 is a diagrammatic view illustrating a carburetor constructed in accordance 55 with the present invention in vertical section, and in cooperative relation to the controlling means therefor;

Figure 2 is a view similar to Figure 1, but illustrating the parts in a slightly different 60 position;

Figure 3 is a similar view illustrating still another position of the parts, and

Figure 4 is a vertical sectional view through a portion of a vehicle dash illustrating one 65 form of controlling means.

In accordance with the present invention, there is illustrated a carburetor comprising a mixing chamber 2 having the usual controlling throttle 3, and provided with an inner 70 venturi 4 for supplying the carburant to the mixing chamber. This carburant may be partly fed, as well understood in the art, from a float chamber 5 leading by a suitable passage 6 to main nozzle 7, and also partly fed by 75 means of an atmospheric well 8 connected by a channel 9 with the auxiliary nozzle 10. Both of these nozzles communicate at their discharge ends with a conduit 11 leading to the inner venturi 4.

In addition to the nozzles just described which constitute the normal fuel feeding means during the operation of the carburetor, there may also be provided a supplemental fuel feeding passage 12 fed from the 80 atmospheric well, and discharging into the mixing chamber 2. The flow of carburant through this supplemental fuel feeding means may be partly controlled by a calibrated orifice or constriction 13 and partly by the 85 amount of air permitted to pass thereto.

For the purpose of controlling the supply of air, I have illustrated a three-way valve 14 having a diametrically extending passage 15 and a radially extending passage 16. When 90 it is desired to start the engine, the three-way valve will be moved to the position illustrated in Figure 1. In this position, the supply of air to the supplemental fuel feeding 95 means and to the conduit 11 will be cut off. 100

At this time, therefore, substantially pure carburant will be fed through the supplemental fuel feeding means 12. After the engine has been operated for a predetermined period sufficient to materially change the temperature thereof, the three-way valve is moved into its normal position, as illustrated in Figure 2. In this position, the diametrically extending passage 15 has its ends in communication with the ports 17, whereby air is permitted to flow therethrough into the radially extending passage 16, and thence past a needle valve 18 into a passage 19 leading to the supplemental fuel feeding means. This will increase the ratio of air to carburant, thereby considerably leaning the mixture fed by the supplemental fuel feeding means. It will, however, have no effect upon the mixture delivered by the inner venturi 4. After a continued operation of the carburetor with the parts in the position just described, the temperature of the engine may be raised sufficiently high to permit the use of still a leaner mixture. In this event, the three-way valve will be operated to bring it into the position indicated in Figure 3. At this time the diametrically extending port 15 will communicate at one end with conduit 11, and at its opposite end with the passage 19, while the radially extending port 16 will communicate with one of the ports 17. This will permit air to pass directly both to the supplemental fuel feeding means and to the main fuel feeding means, thereby decreasing the effective suction on the nozzles 7 and 10 and still further decreasing the ratio of carburant to air. It will be apparent, therefore, that the three-way valve provides convenient means for changing the ratio of carburant to air as may be required for any operating condition of the engine, without changing the effective nozzle outlets or the normal supply of air. In extremely cold weather, however, I have found that even this controlling means may not be effective for obtaining the desired ease of starting. This objection may be largely overcome by providing heating means cooperating with the mixing chamber, or with some other portion of the carburetor, whereby the temperature thereof may, independently of the temperature of the engine, be raised to such a point that vaporization of the carburant is made possible. In the drawings I have illustrated the mixing chamber as being jacketed by a water heater 20, but it will be apparent that after the engine has been standing for some time, such a heater has little, if any, effect. Even where such a heater is provided, its action is preferably supplemented by some other heating means capable of being controlled at will, independently of the temperature of the engine. For this purpose, I have illustrated an electric

heating means, preferably providing separate coils 21 and 22. These coils are adapted to be respectively energized and deenergized in definite relation to the three-way valve 14. For accomplishing this result, there may be provided a suitable controlling switch 23 comprising a movable contact arm 24 and a series of contact segments 25, 26 and 27, respectively. Connected with the segment 26 is one terminal 28 of a suitable source of electric current. The segment 27 is connected by a wire 29 to one side of the coil 21, while the segment 25 is connected by a wire 30 with one terminal of the coil 22. The opposite terminals of both of these coils may be connected by a wire 31 to the opposite side of the source of electric current. With this construction, and with the switch 24 in the position illustrated in Figure 1, current will flow from the source of current to the segment 26, and thence through the switch arm to both the segments 25 and 27. From these segments it will pass respectively through the wires 30 and 29 to the coils 22 and 21, and the circuit will be completed through the wire 31. With the parts in this position, therefore, both of the coils will be energized, thereby exerting the maximum heating influence on the carburetor. This action is desirable, as at this time it is necessary to exert every possible effort to obtain the greatest possible ratio of carburant to air.

When the three-way valve is moved into the position illustrated in Figure 2, the switch arm 24 is simultaneously moved to the position illustrated in this same figure. In this position the segment 25 is disengaged, whereby current flows only to the coil 21. This decreases the heating effect exerted by the heater substantially in proportion to the decrease in the ratio of the carburant to air effected by the movement of the three-way valve.

During the final operation of the three-way valve into the position illustrated in Figure 3, the switch arm 24 disengages the segment 26. At this time, the circuit is broken, both to the coil 21 and to the coil 22, thereby entirely cutting the heater out of circuit. By this time, however, the engine has reached an efficient running temperature, enabling a comparatively lean mixture to be successfully used.

In Figure 4 there is shown, by way of example only, one form of mechanism by means of which the simultaneous operation of the heating means and of the carburant controlling means may be obtained. In this figure the shaft 32 for the three-way valve 14 is shown connected in some suitable manner, as by universals 33, with a shaft 34 leading through a dial 35 on the dashboard of the vehicle and connected to an indicator finger 36 movable over the dial. This dial may bear designations of suitable character, such

as "Start", "Idle" and "Run". Carried by the shaft 34 is the switch arm 24 which controls the operation of the heater. With this arrangement, by merely moving the indicator in the accustomed manner, there is obtained a simultaneous operation of a plurality of controlling means so coordinated that desirable results are obtained. This constitutes one advantage of the present invention.

10 It will be clearly understood that in certain cases it may be desirable to so interconnect the mixture control with the heating means as to have the maximum heating effect for the leaner mixtures. This is particularly true in 15 aviation work, where a leaner mixture is required for the higher altitudes where, as a rule, intense cold exists. In other cases it may be desirable to simultaneously lean the mixture and heat some portion of the carburetor to prevent the same from freezing.

20 It will be apparent that while I have illustrated electrical heating means by reason of the flexibility of operation and ease of control thereof, other heating means may advantageously be utilized. This heating means may be independent of, and supplemental to the normal heat developed by the engine.

25 Still further advantages of the present invention resides from the provision of a single controlling means suitably positioned and capable of being moved to extreme or intermediate positions to progressively effect a changing ratio of carburant to air as necessary for a given engine operation.

I claim:

1. In a plain tube carburetor, an air-vented nozzle delivering a mixture of fuel and air, means independent of the throttle for varying at will the suction effective on said nozzle for varying the ratio of carburant to air delivered by said nozzle during the operating range of the engine, and means simultaneously operable with said first mentioned means for varying the heat effective to vaporize the resulting mixture.

2. In a carburetor, a venturi, a nozzle delivering a mixture of fuel and air to said venturi through a constant area outlet, air bleeding means for varying the effective suction on said nozzle, means operatively connected to said air bleeding means for heating said mixture, and means for simultaneously and progressively controlling both of said means.

3. In a carburetor, a plurality of fuel feeding nozzles, air bleeding means for progressively cooperating with different nozzles, means connected to said air bleeding means for heating the mixture, and means operable at will for simultaneously controlling both of said means.

4. In a multiple venturi carburetor, a nozzle delivering a mixture of fuel and air to the inner venturi through a constant area outlet,

air bleeding means for varying the effective suction on said nozzle, means operatively connected to said air bleeding means for heating said mixture, and means for simultaneously and progressively operating both of said means.

5. In a carburetor, means for heating the carburant with the heat generated by the combustion, means independent of the throttle and of the suction changes in the engine manifold for varying the ratio of carburant to air during the operation of the carburetor, supplemental means for vaporizing the carburant from a source other than the combustion during starting, idling and running periods of the engine, and means for simultaneously operating the last two means.

6. In a carburetor, a nozzle delivering a mixture of fuel and air, means for progressively varying the ratio of carburant to air delivered by said nozzle throughout the operating range of the carburetor, progressively variable means for heating the mixture, and means for simultaneously varying the ratio of carburant to air and for varying the effectiveness of said heating means.

7. In a plain tube carburetor, a nozzle delivering a mixture of fuel and air, means independent of the throttle for varying the ratio of carburant to air delivered by said nozzle during starting, idling and running periods of the engine supplied thereby, a throttle, heating means for the carburetor, and means for simultaneously controlling both of said means throughout the operating range of the engine.

8. In a carburetor, a constant air inlet, a nozzle delivering a mixture of fuel and air, an air vent for said nozzle, a progressively operable valve for progressively varying the ratio of carburant to air delivered by said nozzle during starting, idling and running periods of the engine supplied thereby, a throttle, heating means for the carburetor and means for simultaneously controlling both said valves and said means throughout the operating range of the engine.

9. In a plain carburetor, a throttle, a mixture delivering nozzle adjacent said throttle, means independent of the throttle for varying the ratio of carburant to air delivered by said nozzle during starting, idling and running periods of the engine supplied thereby, heating means for the carburetor, and means for simultaneously controlling both of said means throughout the operating range of the engine.

10. In a plain tube carburetor, multiple venturis in coaxial alignment, a mixture delivering nozzle leading to the inner venturi, a plurality of fuel feeding means cooperating with said nozzle, means independent of the throttle for increasing the amount of air relatively to the amount of carburant delivered by said nozzle throughout the operat-

ing range of the carburetor, and means for changing the temperature conditions in the carburetor at will.

11. In a carburetor, an air-vented jet delivering a mixture of fuel and air, means independent of the throttle and of the suction changes in the manifold for varying simultaneously the heating of the mixture and the ratio of carburant to air delivered by said jet throughout the operating range of the engine.
12. In a carburetor, a U-shaped mixing pipe having a mixture outlet projecting into the carburetor and a free end open to the air, a liquid fuel feed to said pipe, means independent of the throttle and of the suction changes in the engine manifold for simultaneously varying at will the ratio of carburant to air delivered by said mixture outlet throughout the operating range of the engine and the temperature conditions in the carburetor.
13. In a mixing chamber, a pipe having contact with said chamber for delivering a mixture of fuel and air, means independent of the throttle and of the suction changes in the manifold of the engine for simultaneously varying the ratio of carburant to air delivered by said pipe throughout the operating range of the engine supplied thereby and the heating of said mixing chamber, whereby said pipe is heated by conductivity.

In testimony whereof I have hereunto set my hand.

HENRY WILLIAM HAEGLER.
